CLAIM

The ornamental design for a satellite, as shown and described.

DESCRIPTION

FIG. 1 is a perspective view of a satellite showing the new design;

FIG. 2 is a top plan view thereof;

FIG. 3 is a bottom plan view thereof;

FIG. 4 is a front elevational view thereof;

FIG. 5 is a back elevational view thereof;

FIG. 6 is a right side elevational view thereof; and,

FIG. 7 is a left side elevational view thereof.

The broken lines shown represent the portions of the satellite that form no part of the claimed design.
